UNITED STATES PATENT OFFICE.

HEINRICH ROENENBUSCH, OF MUNICH, GERMANY.

FACING-TILE

SPECIFICATION forming part of Letters Patent No. 678,425, dated July 16, 1901.

Application filed April 25, 1901. Serial No. 57,438. (No model.)

To all whom it may concern:

Be it known that I, HEINRICH ROENENBUSCH, a citizen of Germany, residing at Munich, in the Empire of Germany, have invented certain new and useful Improvements in Facing-Tiles; and I do hereby declare the following to be a full, clear, and exact description of the invention, such as will enable others skilled in the art to which it appertains to make and use the same.

The present invention relates to tiles or slabs for facing the walls, ceilings, floors, and other parts of buildings to be used as a substitute for plaster or stucco or other facing ordinarily employed.

The object of the invention is to provide slabs or tiles which may readily be put in place and assembled and which at the same time will be securely held in place when so assembled.

With this object in view my invention consists in a tile or slab made from cement, earthenware, stone, or the like and which is so formed or constructed that it can be readily hung in or attached to a wire fabric or lattice-work or the like in any position, so that when a sufficient number have been put in place they will form a continuous unbroken wall, ceiling, flooring, or the like without requiring any auxiliary fastening means—such as nails, hooks, screws, or the like—and which will not require the arrangement of rabbets, grooves, springs, perforations, studs, or similar securing arrangements or devices.

Slabs or tiles made in accordance with my invention may be used in a great variety of ways—such as, for example, for flooring, (in a horizontal position,) for roofing, (in a slanting position,) for the facing of inner and outer walls, (arranged vertically or in an inclined position,) for ceilings, (suspended horizontally,) and for vaults, in which latter case they may be arranged so as to gradually pass from a vertical to an inclined and finally to a horizontal position.

In the drawings accompanying this specification I have represented a tile embodying my invention in its preferred form.

In the drawings, Figure 1 is a front elevation, Fig. 2 a rear elevation, and Fig. 3 a vertical central section, of such a tile or facing-slab. Fig. 4 represents a portion of a

wall formed from such facing-tiles in elevation; and Fig. 5 represents a vertical section of said wall on line A B, Fig. 4.

As seen from the drawings, the tile or slab A is of polygonal shape—in the present case hexagonal—and is provided at its rough rear face with a suspending-hook *a*, which projects out preferably from the middle portion 60 of the upper edge, as shown. The upper and lower triangular edges of the tile A are beveled in opposite directions at *d* and *e*, as shown, the beveled surfaces in the present case being substantially parallel. The tile 65 is, moreover, provided with a nose *b* above the hook *a* and extending upwardly from the apex of the upper triangular beveled edge *d*, the inner plane surface *b'* of said nose being preferably in line with the rear surface of the 70 tile and forming an acute angle with the upper beveled edge *d*, as shown.

This facing-tile may be used as follows: The wall or other surface of the building which is to be faced is first provided with a supporting-skeleton of wire fabric or, if desired, of lathwork, such as is usually employed as a preliminary step in the facing of walls and the like. This supporting skeleton or framework *c*, Figs. 4 and 5, should be made in dimensions and proportions in such a way as to harmonize with the dimensions of the facing-tiles, so as to provide the proper supports for the supporting-hooks or suspending-hooks *a* at the proper points consistent with permitting the tiles to fit closely together and their faces or front surfaces to form one continuous unbroken surface. In case a framework has already been prepared which does not correspond to the dimensions of the tiles the 90 same must be first provided with the proper supports by arranging thereon wires or laths at the proper points. When the framework is ready, the tiles or slabs A are mounted on the same by suspending them with the hooks 95 *a* from the wires or laths of the frame. When thus hung in place, the lower beveled edges *e* of each tile, which forms an acute angle with the rear face of the said tile, will fit snugly into the acute angular recess formed between 100 the nose *b* and the upper bevel *d*, whereby a displacement of the front or of the rear is effectually prevented, and when all of the tiles have been placed in position on the wall C or

other portion of the building they will practically form one rigid continuous surface, all danger of a separate tile falling out being thus practically avoided.

5 It will be noted that the ear B of each tile forms a stop for the rear surface of the two adjoining tiles just above the tile to which it belongs. The tiles are thus all effectually clamped in position, as above stated.

10 During or after the operation of assembling the tiles the wall or facing formed from these tiles may be plastered from the rear, so as to form a further support, the thickness of which is indicated by the dot-and-dash lines in Fig. 5.

15 What I claim, and desire to secure by Letters Patent of the United States, is—

1. A facing tile or slab having oppositely and parallel beveled upper and lower edges and provided with a suspending-hook at its 20 upper edge, and a nose or stop extending above the said upper edge, the outer surface of the nose and the upper beveled edge forming an acute angle with the rear face of the tile or slab.

2. A facing slab or tile having upper and 25 lower oppositely and parallel beveled edges and provided with a suspending-hook, and a stop or nose at its upper edge, the front of said nose being in line with the rear surface of the tile and forming an acute angle with 30 the upper beveled edge, while the lower beveled edge also forms an acute angle with the rear face of the tile or slab.

3. A facing slab or tile having a lower beveled edge of triangular shape which forms an acute angle with the rear face and an upper triangular beveled edge inclined in an opposite direction, in combination with a suspending-hook and a nose extending from the apex of the upper beveled edge, the outer face of 40 said nose forming an acute angle with the upper beveled edge.

In testimony whereof I affix my signature in presence of two witnesses.

HEINRICH ROSENBUSCH.
